Inventor:
Frank T. Baird,

By Cheever & Cox

At the

UNITED STATES PATENT OFFICE.

FRANK T. BAIRD, OF BLUE ISLAND, ILLINOIS.

ELECTRIC LANTERN.

1,278,824.

Specification of Letters Patent. Patented Sept. 17, 1918.

Application filed December 4, 1916. Serial No. 134,872.

To all whom it may concern:

Be it known that I, FRANK T. BAIRD, a citizen of the United States, residing at Blue Island, in the county of Cook and State of Illinois, have invented a certain new and useful Improvement in Electric Lanterns, of which the following is a specification.

My invention relates to electric lanterns for use in railway service and under other conditions requiring a reliable and efficient device. The present lantern is analogous in some respects to the one shown in my co-pending application Serial No. 134,871, filed on even date herewith and also to the one shown in Patent No. 1,088,120, granted to me February 24, 1914. It will be understood by those familiar with the art that batteries are now obtainable upon the market of a type commonly called "recharge dry batteries." These are similar to the well known dry cells, except that they are especially adapted to be recharged by replenishing the necessary supply of water and then passing an electric current through the battery in the ordinary manner. One of the objects of my invention is to adapt the lantern to use one of these recharge batteries. In accomplishing this, I provide a special water-tight receptacle within the lantern casing, this receptacle containing the battery and being large enough to contain an overflow of water in case water should be spilled during the act of pouring it into the battery, or should escape from the battery. This receptacle is so constructed that it and the recharge battery may be substituted for an ordinary dry battery without changing the construction of the lantern. This object is accomplished by certain expedients which will be explained. Another object of the invention is to provide means whereby the lantern may be quickly and easily caused to show different colors without changing the lamp itself. Another object is to provide means for guarding the lamp so that in case of breakage, it will not ignite gases when used in coal mines or other situations where inflammable gases are apt to be found. Another object is to provide simple and efficient means whereby the lantern may be partially collapsed when not in use.

I obtain my objects by the construction illustrated in the accompanying drawings, in which:

Figure 1 is an elevation of the lantern, partly in axial section.

Fig. 2 is a plan section on the line 2-2, Fig. 1.

Fig. 3 is a side view of the battery receptacle and parts mounted thereon, the central portion being broken away. 60

Fig. 4 is a top view of the battery, showing a portion of the terminal leads.

Fig. 5 is a bottom plan view of the lantern. 65

Fig. 6 is a plan section on the line 6-6, Fig. 1.

Fig. 7 is a perspective view of the shade which guards the lamp and also colors the light rays when a colored shade is selected. 70

Fig. 8 is a perspective view of the wire guard which protects the lamp shade.

Fig. 9 is a perspective view of a gasket suitable for use in connection with the shade. 75

Fig. 10 is a perspective view of one of the clips employed for supporting the lamp shade.

Similar numerals refer to similar parts throughout the several views. 80

The lantern has a portable, main cylindrical casing 1 provided with a cover 2 and suspended by a bail 3 from trunnion pins 4, 4. The casing has a convex bottom 5 with an opening at the center for receiving the base of the lamp 6 which screws into the socket 7. The casing is preferably provided with a stand consisting in the present case of legs 8, 8, the lower ends of which are omitted as their form is not essential. At the upper 90 ends, said legs are fastened to a ring 9 which slides vertically on the outside of the casing. Said ring is a split ring in the present instance and at the proximate ends has flanges 10, 10 which are apertured to receive 95 the clamping bolt 11. Said bolt is provided at one end with a nut 12 and at the other end with an eccentric 13 operated by means of a handle 14. The parts are so constructed that when the handle is in acting position, 100 shown in Fig. 2, it will clamp the ring on to the casing and hold it in any position to which the ring is adjusted. When the handle is thrown back, it causes the eccentric to loosen the ring, whereupon it may be slid to 105 any desired position upon the casing. In this way, the legs or supporting framework may be extended to support the lantern or may be retracted so as to occupy a position practically alongside the casing. In the latter case, the device will occupy but small 110 space.

Within the casing is a stationary frame consisting chiefly of the platform 17 carried by side arms 27, 27 suspended from the trunnion pins. Said platform has a center contact 18 and a ring contact 19. The center contact is electrically connected to the center screw 20 which engages the center contact of the lamp when the latter is in position, as shown in Fig. 1. The ring or outer contact 19 has a lug 21 in position to be engaged by the main switch 22 which is in permanent electric connection with the lamp socket 7. Switch 22 is operated by a screw 24 carried at the lower end of a switch-operating rod 25. Said rod is vertically movable in the casing and is actuated by cam mechanism 26 at the upper end of the rod. Said cam mechanism is operated by the bail 3. The precise mechanism need not be described in detail here as it is not herein claimed and is shown in detail in my companion application hereinabove referred to. It is sufficient for the present purpose to say that by swinging the bail from one side to the other, the rod 25 will be raised and lowered, thus raising and lowering the main switch 22 and illuminating and extinguishing the lamp.

The receptacle, which is shown separately in Fig. 3, consists of a water-tight vessel 30 open at the top and having spring clips 31, 31 at the bottom for yieldingly gripping the sides of the battery 32. These clips consist in the present case of upright resilient fingers rigidly fastened to the inside of the bottom of the receptacle and pressing radially inward to engage the sides of the battery and hold it securely against lateral movement.

A plate 35 is slotted at the ends to receive and be guided vertically by the side arms 27. This plate is fastened to the bottom of the receptacle 30 and hence prevents side-wise motion of the battery receptacle relatively to the main casing. Said plate has a resilient center terminal 36 which is electrically connected to the lower end of a conductor 37 which leads up permissibly along the outside of the receptacle and at the upper end is provided with means whereby to be connected to the battery terminals, for example, a connector 38 by which it is electrically connected to one of the terminals of the battery. A resilient outer terminal 40 is also mounted on the underside of plate 35 and is in electric connection with a conductor 41 which leads upward along the outside of the receptacle, and at the upper end is provided with means whereby to be connected to the battery terminals, for example, a connector 42, as best shown in Fig. 3. These terminals 36 and 40 which are most readily seen in Fig. 3, engage respectively the center contact 18 and ring contact 19, and as they are resilient, they form a cushion for

yieldingly supporting the battery receptacle. The receptacle itself is of somewhat larger diameter than the battery and by preference, extends slightly above the top of the battery. The result is that if water spills over the side of the battery, it will be collected by the receptacle and hence save the internal parts of the lantern from getting wet and becoming fouled. A recharge battery is ordinarily made with a central chamber, open at the top. In my lantern, this chamber is closed by a cap 44 which is held down by a bar 45 over which is a spring 46 secured to the underside of the cover 2. This feature, however, is not herein claimed as it is shown in the companion application.

Secured to the convex bottom of the casing are clips 50, one of which is shown in perspective in Fig. 10. These clips are here shown as three in number, each having a finger 51 adapted to engage a flange 52 formed at the rim of the shade 53. Said shade, which is shown separately in Fig. 7, has notches 54 in the rim, and consequently the shade may be attached by simply applying it to the bottom of the casing, permitting notches 54 to pass the fingers 51 and then rotating the shade a few degrees either to the right or left. A gasket 55, shown separately in Fig. 9, fits into a groove 56, formed in the top of the rim and this creates enough friction to prevent the shade from accidentally rotating and thereby becoming dislodged. The gasket also performs a second function, for it makes the connection between the shade and the casing bottom air-tight. Hence, if the lamp is broken the incandescent filament will not have access to the atmosphere outside of the shade. This is of special importance in mines or other places where inflammable gases are encountered.

The clips 50 also support the guard frame 60, shown separately in Fig. 8. This frame has notches 61 which pass over the outer ends of the clips and permit the frame to be attached. Depending from said frame are guard wires 62 which are preferably in the form of an open basket surrounding the shade 53. Thus, the shade is protected against breakage from striking against external objects.

In operation, if a recharge battery is to be used, the receptacle 30 will first be dropped into place in the casing, the slotted ends of the plate 35 straddling the side arms 27 and the resilient terminals 36, 40 resting upon the center contact 18 and ring contact 19, respectively. The battery may then be lowered into place, its base fitting in between the clips 31 within the receptacle. The connectors 38 and 42 are then made to establish electric connection between the battery terminals and the conductors 37 and 41. The bar 45 is then lowered into place to hold the

cap 44 in position, after which the cover 2 of the lantern is fastened into place. The battery may be recharged without removing it from the lantern, it being simply necessary to remove the lantern cover 2 and the bar 45. Cap 44 is then removed and a sufficient amount of water poured in. Any excess of water, or spilled water, will be collected within the receptacle, thus keeping the casing itself and the contacts in the lower part thereof clean and free. The battery terminals are then disconnected from the conductors 37, 41 and connected to any suitable source of electrical energy. After the battery has been subjected to a charging current for the proper amount of time the parts are replaced and the battery is ready again for service.

As to the shade 53, this may be of any color desired and, in fact, shades of different colors may be substituted quickly and easily. The lantern, therefore, is efficient and practical, especially for railroad, mining and other purposes where certainty and safety are required.

I claim:

1. An electric lantern having a main casing provided with a lamp at the bottom, contacts through which said lamp may be energized, a battery, and a battery receptacle, said receptacle fitting into the casing and having terminals engaging the said contacts when the receptacle is in place, and means at the top of said receptacle adapted to make electric connection with the battery terminals, said means being in permanent electric connection with the respective terminals on the receptacle.

2. An electric lantern having a main cas-

ing, a battery, a lamp, a platform near the bottom of the casing, contacts on said platform through which the lamp may be energized, a battery receptacle within said casing, said receptacle having terminals cooperating with the respective contacts, means leading from said terminals to the top of the receptacle for connection to the battery terminals, said receptacle being of larger diameter than the battery, and means within said receptacle for holding the battery centralized within the receptacle and spaced from the walls thereof.

3. A lantern having a main casing, an electric lamp, a battery having terminals at the top, a battery receptacle within the casing, a plate fastened to the bottom of said receptacle, terminals on said plate electrically connected to the lamp, and means for guiding said plate as it descends within the casing and preventing sidewise movement thereof.

4. A cylindrical electric lantern having a convex bottom with an aperture in it concentric with the axis of the lantern, a lamp projecting through said aperture coaxially therewith, and a basket-like guard of wire for protecting said lamp, said guard having an approximately circular frame with notches therein and the lantern bottom having clips arranged concentrically with the axis of the lantern, said clips passing through the notches when the guard is being positioned and engaging the un-notched portion of the frame when the guard is rotated about its axis.

In witness whereof I have hereunto subscribed my name.

FRANK T. BAIRD.
